UNITED STATES PATENT OFFICE.

CARLE A. MATISSE AND ALBERT C. MATISSE, OF NEW YORK, N. Y.

PROJECTING-LAMP.

1,186,323.

Specification of Letters Patent.

Patented June 6, 1916.

Application filed January 25, 1916. Serial No. 74,245.

To all whom it may concern:

Be it known that we, CARLE A. MATISSE and ALBERT C. MATISSE, citizens of the United States, and residents of the city of 5 New York, borough of Manhattan, in the county and State of New York, have invented a new and Improved Projecting Lamp, of which the following is a full, clear, and exact description.

10 Our invention relates to projecting lamps, and it has reference more particularly to means for concentrating the major part of the light from the lamp in the lower part of the reflector of the lamp.

15 The object of the invention is to provide a simple and efficient lamp which will comply with the various ordinances of large cities without materially impairing the light beam of the lamp.

20 With the above and other objects in view, the nature of which will more fully appear as the description proceeds the invention consists in the novel construction, combination and arrangement of parts as herein fully 25 described, illustrated and claimed.

In the accompanying drawings, forming part of the application, similar characters of reference indicate corresponding parts in both views.

30 Figure 1 is an axial section through our projecting lamp; and Fig. 2 is an elevation of the secondary reflector of the lamp.

Referring to the drawings, 3 is the casing of the lamp, in which a suitable reflector 4 is mounted. It may be a parabolic reflecting surface or a combination in the shape of a lens, as shown. A source of light 5 is provided in the focus of the reflector. The source of light is preferably mounted on a 35 standard 6 which can be adjusted along the axis of the reflector through the medium of a screw 7.

Coöperating with the main reflector 4 of the lamp is a secondary, three-quarters 45 spherical reflector 8. The secondary reflector is mounted in a casing 9 conforming to the curvature of the reflector, and from which a bracket 10 extends along the standard 6. The bracket 10 has an elongated slot 50 11 engaged by a screw 12, whereby the secondary reflector may be adjustably secured to a bracket 13, the bracket 13, in turn, being adjustable on the standard. By means of the screw 12 the secondary reflector may be

adjusted along the standard, and, consequently, the center of curvature of the secondary reflector may be made to coincide with the center of the light source 5 and, therefore, with the focus of the main reflector 4. 55

It will be noted that the missing quarter 60 of the secondary reflector faces the lower, horizontal half of the main reflector, thus the maximum amount of light is concentrated in the lower half of the main reflector. 65 The upper horizontal part of the main reflector only receives light by reflection from the lower horizontal part of the main reflector, for the secondary reflector prevents the direct radiation from the source of light 70 to the upper part of the main reflector above the horizontal.

When the secondary reflector 8 is made of 75 glass, the reflector must be made in two sections 14 and 15. One of the sections is semi-spherical, while the other is only one-quarter of a sphere. The semi-spherical portion 14 is preferably placed into the casing 9 totally above the horizontal plane passing through the axis of the lamp. In consequence the 80 section 15 of the reflector will be below that plane.

By an arrangement as above described, it is possible to use the lamp within cities where special ordinances have been passed 85 forbidding the use of undimmed projecting lamps. This is due to the fact that the light from the upper part of the main reflector, which is the most objectionable is eliminated, while the non-objectionable part 90 of the light, which is in the lower part of the main reflector, is concentrated. The casing 9 is preferably polished on its exterior surface to reduce light absorption to a minimum. 95

We claim:

1. In a projecting lamp, a main reflector, a source of light in the axis thereof, and a three-quarters spherical secondary reflector substantially concentric with the source of 100 light, the missing quarter of said secondary reflector being below the horizontal plane passing through the axis of the main reflector and opposite the main reflector.

2. In a projecting lamp, a main reflector, 105 a source of light in the axis thereof, a three-quarters spherical secondary reflector substantially concentric with the source of light,

the missing quarter of said secondary reflector being opposite the lower, horizontal half of the main reflector.

3. In a projecting lamp, a casing, a main reflector associated therewith, a source of light in the axis of the reflector, a standard carrying said source of light and adjustable in said casing so that said source of light may be moved along the axis of the reflector, 5 and a three-quarters spherical secondary reflector adjustably secured to the standard to be moved transversely of the axis of the 10

main reflector, the missing quarter of said reflector facing the lower, horizontal half of the main reflector.

15

In testimony whereof we have signed our names to this specification in the presence of two subscribing witnesses.

CARLE A. MATISSE.
ALBERT C. MATISSE.
